UNITED STATES PATENT OFFICE.

OLIVER P. HIPPLE, OF WILKINS TOWNSHIP, ALLEGHENY COUNTY, PENNSYLVANIA,
ASSIGNOR TO WESTINGHOUSE ELECTRIC AND MANUFACTURING COMPANY, A COR-
PORATION OF PENNSYLVANIA.

CONTROL APPARATUS.

1,349,380.

Specification of Letters Patent. Patented Aug. 10, 1920.

Application filed January 6, 1917. Serial No. 140,943.

To all whom it may concern:

Be it known that I, OLIVER P. HIPPLE, a citizen of the United States, and a resident of Wilkins township, in the county of Allegheny and State of Pennsylvania, have invented a new and useful Improvement in Control Apparatus, of which the following is a specification.

My invention relates to control apparatus and especially to contact segments that are mounted upon control drums and the like.

The object of my invention is to provide relatively simple and inexpensive means whereby a contact segment of suitable length may be mounted upon a control drum by means of a single screw or other securing means, the curvature of the segment being such that the inner corners thereof may be readily embedded in the drum body, thereby preventing rotative movement of the segment around the screw.

More specifically stated, it is the object of my invention to provide relatively short contact segments, for control drums, having radii of curvature that are materially less than that of the drum itself, whereby the cost of necessary materials is reduced to a considerable degree and the assembly of parts is greatly facilitated.

My invention may best be understood by reference to the accompanying drawing, wherein Figure 1 is a plan view of a control drum embodying my present invention; Fig. 2 is a fragmentary view, in elevation, of the structure shown in Fig. 1; and Fig. 3 is a perspective view of a tool which is preferably employed in connection with my invention.

Referring to the drawing, the apparatus shown comprises a control drum 1 of a familiar type which is preferably composed of wood, or a similar material, and is rigidly mounted upon a central shaft 2, in accordance with a familiar practice; my contact segment 3 and a single screw 4 or other securing means for centrally attaching the segment to the drum body.

The contact segment 3 has a radius of curvature that is materially less than that of the drum body, as is obvious from the corresponding dimension lines 5 and 6, respectively. Consequently, the inner corners 7 and 8 of the contact segment 3 are readily adapted to be embedded in the wooden

drum, thereby serving to effectively prevent 55 rotative movement of the segment around the single screw 4 and also tending to maintain the contact segment in its proper position even after the aperture in the segment has worn to a larger diameter than 60 the screw-head.

The preferred method of assembly of the illustrated contact segment is as follows: The segment 3 is fitted over the screw 4 which is then inserted into the drum body 65 at the proper point and tightened until the inner corners 7 and 8 of the contact segment just touch the drum surface. By then properly alining the contact segment and striking it a couple of well-directed blows, 70 preferably using the setting tool 9 that is shown in Fig. 3, the inner corners 7 and 8 may be readily embedded in the wooden drum, whereupon the screw 4 may be fully tightened. Thus, the contact segment is 75 securely held in its proper position, even though only a single screw 4, with the consequent economy of labor and material, is employed.

A further advantage of the illustrated 80 structure resides in the fact that the contact pressure between the segment 3 and the usual coöperating control fingers (not shown) is gradually increased from the instant of initial contact to the completion of 85 the notch or step of the control drum which corresponds to the central plane of the contact segment.

It will be understood that the advantages 90 of my present invention are best secured in connection with contact segments of relatively short length, such as single-notch segments for reverser drums, for example, although, of course, contact segments of 95 greater length embodying the principles of the present invention may be utilized to advantage, if desired.

I do not wish to be restricted to the specific structural details or arrangement of 100 parts herein set forth, as certain modifications thereof may be effected without departing from the spirit and scope of my invention. I desire, therefore, that only such limitations shall be imposed as are indicated in the appended claims.

I claim as my invention:

1. A contact segment for a control drum located on the cylindrical surface thereof

and having external and internal cylindrical surfaces of radii of curvature less than that of the drum with which the segment is associated.

- 5 2. A contact segment for a control drum having a relatively small radius of curvature with respect thereto, whereby the inner corners of the segment may be embedded in the drum body.
- 10 3. The combination with a control drum of wood or similar material, of a contact segment and a single means for securing said segment to said drum, the segment having a relatively small radius of curvature with respect to the drum, whereby its inner corners may be embedded in the drum body to prevent rotative movement of the segment.
- 15 4. A control drum embodying a contact segment located on the cylindrical surface of the drum and having a radius of curvature less than that of the drum.
- 20 5. A control drum embodying a contact segment having a radius of curvature less than that of the drum and a single securing means for the segment, the edges of said segment being embedded in the body of said
- 25

drum to prevent rotative movement of the segment around said securing means.

6. A control drum embodying a contact segment the inner surface of which has a radius of curvature less than that of the drum and having its inner corners embedded in the drum body, and a single threaded member for securing said segment to said drum.

7. A controller drum having a contact segment of less radius than said drum and driven into the cylindrical surface of said drum.

8. A controller drum of given radius having a contact segment of smaller radius provided with an opening and a single screw located in said opening for securing said segment to said drum, the edges of said segment being embedded in the body of said drum, whereby said segment is maintained in position on said drum, irrespective of whether said screw engages said segment firmly or loosely.

In testimony whereof, I have hereunto subscribed my name this 29th day of Dec., 1916.

OLIVIER P. HIPPLE.
